UNITED STATES PATENT OFFICE.

JOHANN WOTRUBA, OF AACHEN, GERMANY, ASSIGNOR TO EUGENE E. V. SEYFRIED, OF NEWARK, NEW JERSEY.

BOX-FASTENER.

SPECIFICATION forming part of Letters Patent No. 394,320, dated December 11, 1888.

Application filed January 5, 1888. Serial No. 259,845. (No model.) Patented in Germany April 15, 1882, No. 19,961.

To all whom it may concern:

Be it known that I, JOHANN WOTRUBA, a citizen of the German Empire, and a resident of Aachen, Germany, have invented a new and useful Improvement in Box-Fasteners, (for which I have obtained a patent in Germany April 15, 1882, No. 19,961,) of which the following is a specification.

My invention relates to improvements in fasteners for cigar-boxes and for other boxes.

It consists of a supporting-plate fastened to the cover of the box, and a circular locking-plate pivoted to the same and engaged by a hook fastened to the side of the box, combined with means for securing the locking-plate in its extreme positions.

My invention is illustrated in the annexed drawings, in which—

Figure 1 is a top view of part of a box provided with my improved fastening, showing the cover locked. Fig. 2 is a similar view showing the cover unlocked. Fig. 3 is a vertical section in the plane xx , Fig. 1. Fig. 4 is a vertical section in the plane yy , Fig. 2. Fig. 5 is a perspective view of the hook. Fig. 6 is a perspective view of the locking-plate; Fig. 7, an inverted perspective view of the supporting-plate; Fig. 8, a sectional view showing the fastening applied to the cover in a different manner.

Similar letters indicate corresponding parts throughout the several views.

M represents part of the cover of a box, and N part of one of its sides.

A is a circular disk pivoted to a support, B, by means of a pin, p. This support is shown in the form of a circular plate; but it may be of any other desirable shape, or may be omitted and the pivot secured to the cover of the box. This disk A forms a locking-plate. It is provided with a projection, b, for turning it, and with a slot, a, for receiving and holding the hook C. For this purpose one end of the slot a is made large enough for the head of the hook C to pass through, while the remaining part is large enough for receiving the shank of the hook A without allowing the head to pass through.

The supporting-plate B is fastened to the cover of the box by means of prongs s, or by other suitable means. It is provided with a hole, h, through which the head of the hook C passes when the cover of the box is turned down, a corresponding hole, o, Fig. 3, being formed in the cover of the box.

The hook C is fastened to one of the sides of the box by means of nails or prongs. The locking-plate A and its support B are by preference countersunk in the cover of the box, as shown in Figs. 3 and 4, so that none of the parts shall project inside or outside. A modified method of attaching the support is shown in Fig. 8, where the same is attached to the lower side or inside of the cover M.

For securing the plate A in its extreme positions, I provide a locking device consisting of a stop, m, slightly projecting from the lower side of the locking-plate A, and engaging recesses or holes n or n' in the supporting-plate B when the locking-plate is in its extreme positions, Figs. 1 and 2.

Fig. 2 shows the cover of the box turned down and the head of the hook C passed through the enlarged part of the slot a. By pressing against the projection b, so as to turn the locking-plate to the position shown in Fig. 1, the cover is locked to the side of the box.

What I claim as my invention is—

A box-fastening consisting of a supporting-plate, B, fastened to the cover of the box and provided with holes or recesses n n', a circular locking-plate, A, pivoted to the supporting-plate and provided with a hole, h, projection b, and a stop, m, in combination with a hook, C, fastened to the side of the box and engaging the hole h, substantially as specified.

In testimony that I claim the foregoing as my invention I have signed my name, in presence of two witnesses, this 5th day of December, 1887.

JOHANN WOTRUBA.

Witnesses:

CARL ROHMER,
JOH. HECKMANNS.
